UNITED STATES PATENT OFFICE.

JESSE W. SILVER, OF SOUTH TACOMA, WASHINGTON.

BUTTON.

1,109,797.

Specification of Letters Patent. Patented Sept. 8, 1914.

Application filed November 21, 1912. Serial No. 732,722.

To all whom it may concern:

Be it known that I, JESSE W. SILVER, a citizen of the United States, residing at South Tacoma, in the county of Pierce and 5 State of Washington, have invented certain new and useful Improvements in Buttons; and I do declare the following to be a full, clear, and exact description of the invention, such as will enable others skilled in 10 the art to which it appertains to make and use the same.

This invention relates to improvements in buttons, and more especially to those of separable construction.

15 The primary object of the invention is in the provision of a separable button whereby an additional garment such as hose or suspenders may be attached thereto after the overlapping portions of the garment have 20 been brought into interlocking engagement.

A secondary object of the invention is to permit of the reception of a rather thick additional garment under the head of the button at times when it becomes necessary, 25 and a construction wherein said head slides on the shank so that the length of the entire device is reduced when said additional garment is rather thin.

With these and other objects in view, the 30 invention consists of certain novel features of construction and the combination and arrangement of parts as will be more fully described and claimed.

In the accompanying drawings: Figure 1 35 is a vertical section of the complete invention showing the members properly assembled; Fig. 2 is a side elevation of the invention with the members of the fastener detached; Fig. 3 is a bottom plan view of the 40 socket member of the button; Fig. 4 is a cross section taken on the line 4—4 of Fig. 1; Fig. 5 is a similar section taken on the line 5—5 of Fig. 1.

In the illustrated embodiment of the 45 invention the socket member includes a cap 1 which is preferably constructed of sheet metal and of the desired formation, and is provided with an anvil annulus 3 and an eyelet 2 having an annular shoulder between 50 which annulus and shoulder the overlapping portion A of the garment is properly clamped.

The stud member of the button is especially constructed for the purpose and consists of a hollow head 4 to which is movably 55 attached a tubular shank 5 having at its

outer end an expanding and flexible head and at its inner end an outwardly projecting flanged portion 6 which is confined loosely within the hollow head 4 but out of contact therewith whereby the head is adapted to automatically adjust itself to various positions on the garments to be attached thereto. The engaging end of the tubular shank 5 is constructed in the usual manner and is 65 herein shown as having an expanding head 10 adapted to frictionally bind in the opening formed for its reception in the socket member. The two members of the button are thus engaged by a snap connection so 70 that they can be readily attached and detached when desired. The head 10 is provided with an annular flange 9, and secured to said shank is a sleeve 7 also provided with an annular flange 8, between which flanges 75 the garment B is adapted to be bindingly clamped as clearly shown in Fig. 1.

Referring again to Fig. 1 a suspender C or a garment is engaged with the button thus constructed by passing its button-hole 80 D over the head 4 of the button and around the sleeve 7, between the head 4 and the flange 8 of the sleeve. Hence the various elements of the garment or garments referred to may be readily attached and as 85 conveniently separated when desired.

Ordinarily the additional garment C containing the buttonhole D may be thin as seen in Fig. 1, and in that case the hollow head may slide outward on the shank 5 90 until an annular shoulder 11 with which its inner end is provided abuts against the end of the sleeve 7. If, however, the garment C is thick this hollow head 4 may slide inward on said shank until it strikes the flange 95 6. In fact, should the garment be "lumpy" or irregular at the point where it contains the button hole D, the entire head 4 may rock to an extent upon the flanged inner end of the shank 5. This result flows from 100 the fact that the hollow head 4 surrounds said shank somewhat loosely, and as the hollow head 4 is generally disposed toward the body, the pressure of the latter tends normally to push this head outward along 105 the shank. Hence, the use for the annular shoulder 11 which abuts against the end of the sleeve 7 when this hollow head has been pushed outward as far as possible, as shown in Fig. 1.

110 From the foregoing description it may be readily seen that the parts as constructed

are adapted to allow for the various movements of the body of the wearer, and further that the garment C can be readily connected and disconnected from the button 5 with convenience.

It will thus be seen that by assembling the parts as described, not only the overlapping portions of a garment can be conveniently connected and detached, but efficient means are provided for holding an additional article of wearing apparel in movable engagement with the overlapping portions of the garment when connected.

From the foregoing description taken in connection with the accompanying drawings, the construction and operation of the invention may be readily understood without requiring a more extended explanation.

Various changes in the form, proportion and the minor details of construction may be resorted to without departing from the principle or sacrificing any of the advantages of the invention as claimed.

What is claimed is:

A separable button of the character described comprising a socket member; a stud member including a shank having attached to it a resilient head at one end adapted to enter said socket member and having a flange at its other end, and a sleeve secured around the shank of this member with its inner end spaced from said flange; and a hollow button-head loose on the shank between the inner end of said sleeve and the flange of the shank, the button head having an annular shoulder adapted to make contact with the inner end of said sleeve when this head is pushed outward on the shank, for the purpose set forth.

In testimony whereof I have hereunto set my hand in presence of two subscribing witnesses:

JESSE W. SILVER.
